UNITED STATES PATENT OFFICE.

HUGH M. DAVISON, OF HUBBARD, TEXAS.

DEVICE FOR MAKING CASTINGS.

No. 919,136.

Specifications of Letters Patent. Patented April 20, 1909.

Application filed June 30, 1908. Serial No. 441,161.

To all whom it may concern:

Be it known that I, HUGH M. DAVISON, a citizen of the United States, residing at Hubbard, in the county of Hill and State of 5 Texas, have invented certain new and useful Improvements in Devices for Making Castings, of which the following is a specification.

This invention relates to molds or flasks 10 for making castings of various kinds, and more especially for making castings for dental use; and the object of the invention is to provide an improved molding apparatus comprising a mold or flask, a tightly fitting 15 cover for the same, means for applying said cover at the proper time to form a hermetic closure, and means for subjecting the molten metal within the mold or flask to pneumatic pressure whereby it shall be forced into every 20 fissure or opening prepared for its reception, thus forming a very perfect and useful casting.

With these and other ends in view which will readily appear as the nature of the invention 25 is better understood, the same consists in the improved construction and novel arrangement and combination of parts which will be hereinafter fully described and particularly pointed out in the claims.

30 In the accompanying drawing has been illustrated a simple and preferred form of the invention; it being however, understood that no limitation is necessarily made to the precise structural details therein exhibited, 35 but that changes and alterations and modifications within the scope of the invention may be resorted to when desired.

In the drawing:—Figure 1 is a side elevation, partly in section of an apparatus constructed in accordance with the invention. 40 Fig. 2 is a sectional detail view taken on the plane indicated by the lines 2—2, in Fig. 1.

Corresponding parts in both figures are denoted by like characters of reference.

45 A suitable base 5, is provided with uprights 6, 6, supporting a platform 7, upon which is mounted a vertically disposed cylinder 8. The base 5 is provided with a vertical recess or socket 9 for the reception 50 of a shank 10 projecting downward from a vertically movable table 11, a coiled expansion spring 12 being disposed in the socket 9 below the shank 10 and pressing upward against the latter, thus forcing the 55 table 11 normally in an upright direction. The recess 9 may be surrounded by a flange

or boss 13. The table 11 supports the flask 14, which is of ordinary construction.

The platform 7 constitutes the lower head of the cylinder 8, which latter contains a piston 15, the stem of which 16, projects through the head or platform 7 and carries a lid or cover 17 adapted to fit tightly upon the flask 14. A spring 18 coiled upon the stem 16 engages the under side of the piston 15 and serves to force the latter normally in an upward direction. The upper end or head 19 of the cylinder 8 has an inlet nozzle 20, which is connected by a pipe or duct 21 with a suitable source of supply of compressed air, the nozzle 20 being provided with a cock or valve 22 whereby the supply of air may be regulated, and cut off when desired.

The stem 16, carrying the lid 17 has a recess or socket 23 extending through said lid, and it has a nipple 24, communicating with the recess 23, and connected by a flexible pipe or duct, such as a rubber hose 25 with a similar nipple 26 extending through the wall 80 of the cylinder 8. The nipple 26 is located in such a position that when the lid 17 engages the flask 14, the piston 15 shall have passed downward in the cylinder a sufficient distance to carry it below the nipple 26, thus 85 placing the latter in communication with the space between said piston and the upper extremity of the cylinder.

The operation and advantages of this invention will be readily understood from the 90 foregoing description, taken in connection with the drawing. The metal placed in the flask having been melted by means of the blow pipe, the cock or valve 22 is turned so as to admit compressed air into the upper 95 end of the cylinder 8, thus forcing the piston 15 in a downward direction until the lid 17 carried by the piston rod engages the flask, forming a tight closure for the latter. The instant the lid engages the flask, the piston 100 15 will have been carried below the nozzle 26, thus permitting compressed air to escape from the upper end of the cylinder through the duct 25 to the recess 23 in the lower end of the piston rod. The molten metal in the 105 flask will thus be subjected to the pressure of the compressed air, and it will be forced into every one of the fissures prepared for its reception, thus making a very solid and perfect casting. As soon as the communication 110 with the source of supply of compressed air is cut off from the upper end of the cylinder,

the piston 15 with its related parts will be restored to normal or initial position by the action of the spring 18.

The table 11 which supports the flask being supported by the cushion spring 12, as herein described, every tendency to a violent shock or jar when the lid 17 on its downward movement comes into contact with the flask, will be avoided.

Having thus described the invention, what is claimed is;

1. In an apparatus of the class described, a vertically movable spring supported flask, a vertically movable lid for the same, and pneumatic means for forcing the lid in the direction of the flask.

2. In an apparatus of the class described, a vertically movable spring supported flask, a vertically movable lid for the same, pneumatic means for forcing the lid in the direction of the flask, and spring-means for restoring the lid to initial position.

3. In an apparatus of the class described, a vertically movable spring-supported flask, a vertically movable lid for said flask, pneumatic means for forcing the lid in the direction of the flask, and means for placing the interior of the flask in communication with a

source of supply of compressed air subsequently to the seating of the lid upon the flask.

4. In an apparatus of the class described, a vertically movable resiliently supported table, a flask upon said table, a cylinder supported above the flask, a spring supported piston movable in the cylinder and having a stem carrying a lid for the flask, said stem being provided with a recess extending through the lid, valved means for placing the upper end of the cylinder in communication with a source of supply of compressed air, and a flexible duct connecting the cylinder with the recess in the valve stem and the lid carried thereby, said flexible duct being connected with the wall of the cylinder at a point which is above the piston when the latter is at the downward extremity of its movement, and the lid is seated upon the flask.

In testimony whereof I have hereto affixed my signature in the presence of two witnesses

HUGH M. DAVISON.
